UNITED STATES PATENT OFFICE.

EDWARD H. GIESY, OF WYOMING, OHIO, ASSIGNOR, BY MESNE ASSIGNMENTS, TO THE LOCKLAND LUMBER COMPANY, OF LOCKLAND, OHIO, A CORPORATION OF OHIO.

REFRIGERATOR.

SPECIFICATION forming part of Letters Patent No. 687,013, dated November 19, 1901.

Application filed March 10, 1899. Serial No. 708,473. (No model.)

To all whom it may concern:

Be it known that I, EDWARD H. GIESY, a citizen of the United States, and a resident of the town of Wyoming, in the county of Hamilton and State of Ohio, have invented certain new and useful Improvements in Refrigerators, of which the following is a specification.

The several features of my invention and the various advantages resulting from their use, conjointly or otherwise, will be apparent from the following description and claims.

Among the features of my invention one of the most important is that which relates to a general arrangement of an ice-box at one side in combination with a compartment or compartments covered with a vitrified lining, substantially as hereinafter set forth.

In the accompanying drawings, making a part of this application, and in which similar letters of reference indicate corresponding parts, Figure 1 is a vertical central section of a refrigerator, illustrating my invention, the section being taken in the plane of the dotted line 1 1 of Fig. 2, that face of the section being shown which faces toward the door. Fig. 2 is a vertical transverse section of the refrigerator, taken in the plane of the dotted line 2 2 of Fig. 1, that face of the section being shown which faces toward the left in Fig. 1. Fig. 3 is a fragmentary section taken through the lower part of the ice-chamber, the section being taken in the plane of the dotted line 3 3 of Fig. 1, that face of the section being shown which faces toward the right in said Fig. 1. Fig. 4 is a top view of one of the crocks. Figs. 5 and 6 illustrate the form of crock when one crock occupies the entire division D. Fig. 5 is a vertical section of the said crock, that face of the section being seen which would face toward the left in Fig. 4. Fig. 6 is a vertical section of the same, taken in the plane of the dotted line 6 6 of Fig. 5.

A indicates the casing or outer shell of the refrigerator. The sides, front, and rear may be paneled or smooth or otherwise formed in an ornamental manner, as desired. The sides, front, and back are preferably insulated—that is to say, they contain a layer or stratum of a suitable non-conductor of heat. Thus in the illustrative case before us a

space W is present between the outer casing and inner casing of the outward frame or shell of the refrigerator, and this space is filled with a substance which will not readily conduct heat. In the present instance these spaces W are packed with mineral wool.

The refrigerator is divided vertically into two main divisions by means of a central partition B. One of these divisions C is the ice-compartment, whose novel formation will be shortly described, and the other division D consists of one or more compartments E. The ice-compartment is everywhere surrounded with a suitable lining Z, preferably a metallic one of zinc or the like. The upper portion of this compartment has vertical sides. Lower down it has at front a ledge or shoulder C³ and at rear a ledge or shoulder C⁴, and from this point the linings Z, leaving the sides of the refrigerator, approach one another as they descend, forming the front and rear inclined walls C⁴ C⁴. Another wall C⁵ on that side of the compartment C opposite to compartment E also inclines away from the adjacent wall of the refrigerator and downward toward the compartment E. Thus these three walls C⁴, C⁴, and C⁵ inclining downward toward one another at last reach a common bottom or platform C⁶, of small dimensions, in which the open upper end of the drip-pipe C⁷ is located. Thus all liquid resulting from the melting of the ice is carried downward and brought into the drip-pipe at a point near to compartment E. Just above or not far above this floor C⁶ the wall of partition B of the refrigerator is provided with an opening B², preferably circular, through which the cold air from the ice-compartment is permitted to enter the lower portion of the division D.

In order to protect the edges of partition B at opening B² and to prevent any moisture or liquid flowing down that surface of partition B which is in compartment C, I provide an annular flanged guard B⁸ and locate the same at the edge of the opening B², the guard projecting into the compartment C, substantially as shown. Any moisture or liquid flowing down the partition B on the side of compartment C and which would otherwise run into the opening B² is caught by the guard.

flange B³ and carried around the edge or side opening and delivered into the bottom C⁶ below, substantially as shown. It will thus be observed that the cold water in ice-compartment C is all of it approximated to opening B² and assists in keeping cool the air which passes down through the ice-compartment. The ice is duly upheld and in the present illustrative instance by a simple construction heretofore indicated—viz., by the ledges or supporting-surface C³. These support the cross-bar ends R² of the rack R, the longitudinal pieces R³ of the rack extending in parallel lines from one cross-bar R² to the other and duly fixed to each of the same. The ice rests upon such a rack as this. Provision is made for the admission of ice into the ice-compartment, and in the present illustrative instance the ice is admitted through opening P, closed by means of a door Q, and this door is preferably provided with an insulated interior cover Q³. The door is hinged at Q³, and the opposite free edge of the door duly rests upon the top portion of the adjacent walls of the refrigerator. Admission to compartment D is duly provided. In the present instance there is a single opening in the refrigerator in front of the compartment D, and this opening is closed by the door F, duly hinged. The construction of this door as regards its being provided with walls—i. e., non-conducting material—is similar to the construction of the rear side of the refrigerator. Provision is made whereby the cold air coming from the ice-compartment C in the compartment D can pass upward in front of the space occupied by the compartment D and also within the said compartment D near the rear thereof. This compartment is lined with porcelain or vitrified material, substantially as shown, the front of the porcelain compartment or compartments being open while the back thereof is entirely closed. That portion of the cool air which does not flow up between the door and this porcelain compartment or compartments flows up on the inside of the said compartments near the rear and in front of the latter.

The preferred construction of the refrigerator is duly illustrated in Figs. 1 and 2, in which case the compartment D is divided into two subcompartments E E, and each of these is composed of or lined by a crock or casing formed of vitrified material, open at front, closed at rear, and provided with sides, top, and bottom. The lower crock is provided at one side with an opening B², and there is an opening E² in its roof or top near its back side. The upper crock or compartment E is provided with an opening E³ in its bottom, located near its back side, and this opening E³ alines with the opening E² in the roof of the lower crock. The two crocks may be set one upon the other, but preferably are separated by partitions or cleats A², and in the event of this shelving A² being present the latter is provided with an opening which co-

incides with the openings E² and E³, so that the partition presents no obstacle to the air passing up through the openings E² E³ from the lower crock into the upper crock E. The upper crock E is also provided in its roof with an opening E³ near its back side, and what air does not pass up between the front side of the refrigerator and the front edge or top of this crock will pass up through this upper opening E³ and into the passage-way G above the upper crock E, and thence over the top of partition B—viz., through the opening H into the upper portion of the ice-chamber C. Thus a current of air is continually maintained within the refrigerator as follows: The air being cooled by the ice in compartment C passes downwardly around the ice and between the bars of the rack R into the chamber C L, constituting the lower portion of chamber C, and thereby having become intensely cold passes through opening B² into the lower portion of compartment D—viz., into the lower crock E—and fills said compartment, and there takes up heat from the articles of provision placed therein and passes up, and as it becomes heated some of it passing up between the door and the front adjacent edges of the crocks E E, and the rest of this air passing up through openings E² E³ of these crocks into the upper crock E and there withdrawing heat from the provisions therein again divides and part of it passes up behind the front of the refrigerator and in front of the roof of the upper crock and the other part passes up through the upper opening E³ of the upper crock, and all of this heated air passes into and through chamber G through opening H into ice-compartment C. Here this air is again cooled and at the same time deposits upon the ice the infinitesimal particles of odor and the like, which are taken up from the food in the upper and lower crocks E E of compartment D. Where the compartment is what may be termed “one” compartment L E—that is to say, where there is only one porcelain crock and that takes the place of the two crocks E E—this vitrified crock is provided with an opening B², located near its lower end, so as to register with the opening B² through partition B, as hereinbefore indicated and in the same manner as the opening in the lower crock E fits the opening in partition B, and there is in the roof of this crock L E an opening E³, located near its back side and substantially similar to that shown in the upper crock E of Fig. 2. Where one large crock L E is present, it will be provided with suitable lugs or projections S on its inner sides for the sustaining of racks crossing from one projection to the other, lying in the same horizontal plane. The preferred shape of these lugs in cross-section is that of a “bead,” as that term is used in the parlance of carpenter work. I have located one of these sets of projections S, usually the lower ones, so that their plane, if extended, would pass through the center or near the center of the opening

B². Thus the rack located upon these last-named projections will be in such a position that the cold air coming in from the ice-compartment C will part of it go below said rack and part of it go above the said rack. The openings E² and E³ are substantially as shown in Fig. 2. The opening in the bottom may be one long continuous slit or be divided by a cross-piece or neck T, preferably employed in the case of large crocks to strengthen them. The upper crock E is also provided with a ledge or projection E⁴, located immediately in front of the opening E³, and in order to make the upper crock reversible there is a similar projection provided on the lower side of the roof of the crock and immediately in front of the opening E³. The function of this projection is to prevent the food or provisions placed upon the bottom of the crock from being pushed too far back, and thus stopping the opening E³ in the rear of the crock or falling down through the same. The ledge also is of benefit in preventing any liquid spilled upon the floor of the upper crock from dripping down through opening E³ into the crock below. Where the partition A² is present between the door and the lower crocks, the front edge of it is preferably provided with a cleat A³, which extends up and down in front of the front edges of the adjacent portions of the upper and lower crocks and forms a finish.

Among the various obvious advantages resulting from the use of my invention and its several features is the following one, viz: The arrangement makes a very cold refrigerator because the ice is located very near the opening from the ice-compartment into the food-compartment. The ice rests just above or near to where the cold air is carried into the food or preserving chamber, and the ice-chamber itself is alongside of and on a level with the upper part of the provision-division D, so that there is no excessive distance to be traversed by the air-current, which merely moves laterally across the top of partition B and in an opposite direction through opening B² in its circulation between the divisions C and D. The tops of the crocks also serve to afford a better circulation through the provision-compartments of the rising air from opening B² by causing said air to divide so that one portion flows up next to the door F, while another portion of such air passes up through the openings E² E³ in the back parts of the crocks. In their function of thus assisting in circulating the air through the provision-divisions the tops of the crocks or linings constitute horizontal partitions extended across the provision-division and provided with openings near their front and back edges, through which the air may pass upward. As the air circulates around the ice the odors, which are minute particles and are given off by the food, are deposited on the ice, so that at the time the air first travels around the ice and travels back into the food-compartments it is entirely freed from the odors it contains.

Hence food of a delicate nature, such as butter and milk, deposited in the lower part of the compartment is not tainted by food of strong odors kept above in the compartment.

I have hereinbefore employed the words "vitrified" and "porcelain" in connection with the material of which the crocks are composed and desire it to be understood that the material of which the crocks are made may be stoneware or any other vitrified substance or material covered with a vitrified glaze or glaze formed on the article by heat and that such classes of material are to be understood as constituting the substances out of which the crocks or linings of the provision-compartments are made.

What I claim as new and of my invention, and desire to secure by Letters Patent, is—

1. In a refrigerator having its body provided with a partition extended across its interior to produce an ice-division and a provision-division side by side, said divisions being adapted for communication at their upper ends, above the top of said partition, and said partition having at its lower part but at a distance above the bottom of the provision-chamber an opening adapted for the passage of air from the ice-division to the provision-division, the provision-division being provided near its top with a partition extended across it and provided with openings for the passage of air, the ice-holding chamber being opposite that upper part of the provision-chamber which is above the cross-partition in the latter, substantially as set forth.

2. A refrigerator having its body divided to produce an ice-division and a provision-division, and having in said provision-division a vitrified lining provided at its lower part with opening at a distance above the floor for receiving air from the lower part of the ice-division, and having its top extended to form a partition across the provision-division, the front edge of the top being spaced away from the wall of the body to form an opening for uprising air, and the back part of said lining top being also provided with an opening for uprising air, that portion of the compartment which supports the ice being abreast of the upper division of the provision-chamber, rack R³, on a level with the floor of the upper division of the provision-chamber, and drip-chamber below communicating with the opening into the side of the provision-chamber, substantially as set forth.

3. A refrigerator having its body divided to produce an ice-division and a provision-division, and having in said provision-division a plurality of vitrified linings arranged one above the other and having their tops extended to form partitions across the provision-division, the front edge of the top of each lining being spaced away from the wall of the body to form an opening for uprising air, and the back part of the top of each lining and also the back part of the bottom of the upper lining being provided with corresponding

openings for uprising air, and the lower lining having at its side an opening leading to the lower part of the ice-division, a drip-chamber below the ice-chamber being opposite the opening into the side of the provision-chamber and adapted to furnish very cold air to the latter, substantially as set forth.

4. A refrigerator having its body divided to produce an ice-division and a provision-division, said divisions being adapted for communication at their upper parts, and the ice-division having an ice-rack arranged across it and dividing it into an upper ice-chamber and a lower cold-air chamber the walls of which are made sloping and contracted toward the bottom of the chamber, one of said walls having an opening extending into and adapted for the delivery of cold air to the lower part of the provision-division, the division for holding the ice being above the chamber with sloping walls, and separated therefrom by a rack, and being located abreast of the upper division of the provision-chamber, substantially as set forth.

5. A refrigerator comprising a body having

a vertical partition extended across it, to produce an ice-division and a provision-division, said partition having its upper end spaced away from the top of the body to produce an air-passage leading from the provision-division to the ice-division, a door at the front of the provision-division, a lower vitrified lining arranged in the provision-division and having in one side an opening adapted for receiving cold air from the lower part of the ice-division, and in its top an opening near its rear wall for the passage of rising air, an upper vitrified lining arranged in the provision-division and having in its bottom and top, openings near its rear wall for the passage of rising air, said linings being open at front and having their front edges spaced away from the door of the provision-division to provide a passage for uprising air, substantially as set forth.

EDWARD H. GIESY.
